UNITED STATES PATENT OFFICE.

HENRI G. CHATAIN AND WILLIAM EVERETT VER PLANCK, OF ERIE, PENNSYLVANIA,
ASSIGNORS TO GENERAL ELECTRIC COMPANY, A CORPORATION OF NEW YORK.

SYSTEM OF ENGINE-COOLING.

1,117,976.

Specification of Letters Patent.

Patented Nov. 24, 1914.

Original application filed May 13, 1912, Serial No. 696,976. Divided and this application filed May 13, 1913. Serial No. 768,547.

To all whom it may concern:

Be it known that we, HENRI G. CHATAIN and WILLIAM E. VER PLANCK, citizens of the United States, residing at Erie, county 5 of Erie, State of Pennsylvania, have invented certain new and useful Improvements in Systems of Engine-Cooling, of which the following is a specification.

The present application is a division of 10 our application, Serial No. 696,976, filed May 13, 1912, which division is made under the requirements of the United States Patent Office.

The present invention relates to motor 15 cars in which an internal combustion engine is employed for propelling purposes, and more especially for such cars where the engine drives an electric generator and the latter supplies current to motors mounted 20 on one or more of the trucks. The engine and generator are mounted in the front end of the car, the remainder being devoted to passengers, baggage, etc. In such an equipment a means must be provided for dissipating 25 the heat of the circulating water that passes through the jackets of the engine cylinders.

The object of our invention is to improve 30 the construction and arrangement of such cooling means whereby the engine will be effectively cooled and this without the use of a circulating pump or pumps.

For a consideration of what we believe to 35 be novel and our invention, attention is directed to the accompanying description and claims appended thereto.

In carrying out our invention the cylinders and exhaust valves of the engine are provided with suitable jackets to permit the 40 circulation of cooling water. These jackets are divided into right and left hand groups or sets which are connected by flexible pipes or hose of large diameter to a two-part radiator that is mounted on and conforms to 45 the shape of the roof of the car as nearly as possible. Such an arrangement has the advantage that a very large surface area for cooling may be provided. By locating the radiator on the roof it is practically free 50 from danger of injury; it is out of the path of dust and dirt, and is subject to the maximum cooling effects of the currents of air when the car is in motion.

In the accompanying drawings which

illustrate one of the embodiments of our 55 invention, Figure 1 is a diagrammatic view of the cooling system; Fig. 2 is a view partly in section and partly in elevation of an indicator to show the level of water in the radiator; Fig. 3 is a longitudinal section 60 view showing one of the headers or the radiator and the overflow tank, and Fig. 4 is a detailed view showing the arrangement of the conduits for conveying water to and from the cooling jackets of the engine cylinders.

Referring to Fig. 1, 10 indicates the floor of the cab containing the apparatus, 11 a side wall thereof, and 12 the curved roof. 13 indicates the main internal combustion 70 engine for propelling the vehicle. It is provided with cylinders 14 and 15 arranged in sets of four each. 16 indicates a small internal combustion engine for driving a generator for lighting the car and driving an 75 air pump, the latter supplying compressed air for starting and braking, etc. The radiator comprises two principal parts or elements, one on the right-hand side and the other on the left-hand side of the car, said 80 radiator being located above the roof and corresponding approximately in shape to the curvature thereof. Each element is provided with a horizontal header 17 located at approximately the center of the car roof, 85 and a smaller horizontal header 18 located near the side, said headers extending longitudinally of the car. Connecting these headers are rows of outer tubes 19 and rows of inner tubes 20. Only two of these tubes 90 in each part of the radiator are shown, but it is to be understood that a multiplicity of such tubes is provided. Each tube is provided with radiating fins 21 of suitable construction. Cooling water after leaving the 95 radiator flows from the lower header 18 by a flexible pipe, such as a piece of rubber hose 22, to the jackets on the left-hand set of the engine cylinders. It is necessary to provide a flexible connection at this point 100 on account of the fact that the engine 13 has a certain limited amount of movement independently of the car body. The water after circulating through said jackets flows upwardly by connection through the pipe 23 to 105 the header 17. The right-hand set of engine cylinders is similarly connected to the right-hand section of the radiator.

In Fig. 4 one set of engine cylinders is shown in side elevation. They are provided with jackets of any suitable construction and circulating water is admitted thereto by the 5 vertical pipes 24 and the horizontal pipes 25 and 26. 27 indicates the pipes that connect the casings of the exhaust valves. The pipes 24 are united at the top by the conduit 28 made in the form of a Y and to which the 10 flexible pipe 22 is connected. The circulating water is discharged from the jackets by the conduits 29 and 30 which are connected to conduit 31, Fig. 1, also made in the form of a Y. This conduit is connected by a 15 piece of rubber hose or pipe 23 with the header 17, Fig. 1, and through which the heated water flows upwardly by convection. Referring to this latter figure the arrows indicate the direction of the flow of the 20 circulating water through the jackets. 32, Fig. 1, indicates a pipe that forms a downward continuation of the conduits 24 and which is connected with the filling connection 33 that is under the control of a valve 34. Said connection 33 can be used either 25 for filling the cylinder jackets and the radiator or for draining them by opening the valve 34. 35 indicates an equalizing pipe for the engine jackets. This contains a 30 valve 36. When the valve is open the water levels in the parts of the radiator will be equalized through this connection and the pipes 32. When it is closed one set or group of engine jackets can be cut out of service. 35 Such an arrangement is desirable when for any reason one section of the radiator is injured or something happens to the operating mechanism of one-half of the engine. In other words, this permits of a partial 40 operation of the car instead of total failure as would be the case if the cooling system entirely failed.

In order to avoid overheating incident to low water in the radiator an indicator is 45 provided of the character shown in Fig. 2 in which 40 indicates a tubular chambered member containing a body of water. Supported by the water is a hollow metal float 41 that is connected to a vertically movable 50 tube 42. Located within this tube is a second and fixed tube 43 which rises considerably above the predetermined maximum level of the water. Extending through the tube 43 and attached to the outer end of the 55 float tube 42 is a small rod 44, to the lower end of which is attached an indicator 45 that by comparison with a flat plate 46 indicates the position of the float 41 in the float chamber, and, therefore, a level of the 60 water therein. Preferably the plate 46 is painted with different colors so that the attention of the operator will be more readily attracted, particularly when the water is getting low. As shown, the tubular member 40 extends upwardly through the header

17 and also through the overflow tank 47 which is mounted on top of the header. 19 and 20 indicate the tubes extending from the upper to the lower header. The lower end of the tubular member 40 is perforated 70 at 48 to permit water to enter the float chamber from the water chamber 49 of the header. A guard 50 is also provided which stands in front of the opening 48 and acts to prevent the movement of the water in 75 the chamber 49 due to car movements from directly affecting the float.

Referring to Fig. 3, we have shown one of the headers 17 in longitudinal section, the tube openings being omitted for simplicity. In order to further improve the operation of the cooling system an overflow tank 47 is provided whose cubical contents are preferably a little greater than those of the water jackets of the engine so that in the event of the engine becoming overheated and generating steam an amount of water equal to the contents of the jackets may be discharged from the headers into said overflow tank. The transfer of water from one tank to another takes place through the openings 51. This overflow tank is also useful when the car is climbing a steep grade because water that might otherwise run out of the radiator through one of the filling holes at 90 the top is caught in said tank and returned to the radiator as soon as the conditions become normal.

The water jacket 52 of the auxiliary engine 16, Fig. 1, receives its supply from the 100 pipe 32 of the right-hand set of engine jackets. After passing through the jacket 52 the water flows by the pipe 53 to the upper right-hand header 17 from which it flows through the radiator tubes 19 and 20 to the 105 right-hand lower header 18 and thence through the pipe 22 back to the jackets on the right-hand set of engine cylinders.

In accordance with the provisions of the patent statutes, we have described the principle of operation of our invention together with the apparatus which we now consider to represent the best embodiment thereof; but we desire to have it understood that the apparatus shown is only illustrative, and 115 that the invention can be carried out by other means.

What we claim as new and desire to secure by Letters Patent of the United States, 120 is:—

1. In combination, a multi cylinder engine having cooling jackets divided into groups, a divided radiator, conduits connecting the jackets of each group in multiple and one group of jackets to each part 125 of the radiator, and fluid carrying means connecting the parts of the radiator.

2. In combination, a multi cylinder engine having cooling jackets divided into groups, a divided radiator located above 130

- the engine, conduits connecting the jackets of each group in multiple and one group of jackets to each part of the radiator, and a fluid carrying conduit connecting the jackets of the groups and forming an equalizing connection between them.
3. In combination, a multi cylinder engine having cooling jackets divided into groups, a divided radiator located above the engine, conduits connecting the jackets of each group in multiple and one group of jackets to each part of the radiator, a fluid carrying conduit connecting the jackets of the groups and forming an equalizing connection between them and a fluid carrying means that connects the parts of the radiator.
4. In combination, a vehicle, having a roof, a multicylinder engine carried by the vehicle and having cooling jackets arranged in independent groups, a divided radiator horizontally disposed on the roof of the vehicle whose tubes are displaced in a manner to conform approximately to the shape of the roof, conduits connected to the respective groups of jackets to receive the hottest water therefrom, said conduits communicating with higher portions of the divisions of the radiator and other conduits that receive the cooled water from lower portions of the respective divisions of the radiator and convey it to the lower ends of the respective groups of jackets.
5. In combination, a multi cylinder engine having cooling jackets arranged in independent groups, a divided radiator, one portion of which is connected to one group of jackets and another portion to another group, and means for cutting any one of the groups out of communication with its part of the radiator.
6. In combination, a vehicle, a multi cylinder engine therein having water jackets arranged in groups, a divided radiator carried by the vehicle and located above the engine, each part of said radiator having headers and connecting tubes, an overflow tank that is above the radiator and is connected to headers thereof, and conduits connecting the groups of jackets to the parts of the radiator.
7. In combination, a vehicle, a multi cylinder engine therein having water jackets arranged in groups, a divided radiator carried by the vehicle and located above the engine, each part of said radiator having an upper and a lower header, an overflow tank that is connected to the upper headers of both parts of the radiator, conduits conveying cooled liquid from the lower headers directly to the jackets, and other conduits conveying heated liquid from the jackets directly to the upper headers.

In witness whereof, we have hereunto set our hands this 16th day of May, 1913.

HENRI G. CHATAIN.
WILLIAM EVERETT VER PLANCK.

Witnesses:

HERMANN LEMP,
O. T. FOUCHE.

It is hereby certified that in Letters Patent No. 1,117,976, granted November 24, 1914, upon the application of Henri G. Chatain and William Everett Ver Planck, of Erie, Pennsylvania, for an improvement in "Systems of Engine-Cooling," an error appears in the printed specification requiring correction as follows: Page 1, line 61, for the word "or" read *of*; and that the said Letters Patent should be read with this correction therein that the same may conform to the record of the case in the Patent Office.

Signed and sealed this 26th day of January, A. D., 1915.

[SEAL.]

R. F. WHITEHEAD,

Acting Commissioner of Patents.
